UNITED STATES PATENT OFFICE.

ROBERT B. COGAN, OF SWISSVALE, PENNSYLVANIA.

DISPENSING-RECEPTACLE.

1,189,347.

Specification of Letters Patent.

Patented July 4, 1916.

Application filed May 14, 1915. Serial No. 28,168.

To all whom it may concern:

Be it known that I, ROBERT B. COGAN, a resident of Swissvale, in the county of Allegheny and State of Pennsylvania, have invented a new and useful Improvement in Dispensing-Receptacles, of which the following is a specification.

This invention relates to receptacles for holding and carrying gasoline, illuminating 10 oils or other volatile, combustible liquids.

The object of the invention is to provide a safe can or receptacle of this kind, which is constructed and arranged to prevent escape of fumes or gases or accidental ignition of 15 the liquid, and one which can be readily manipulated in pouring the liquid into or from the can, which prevents loss of liquid, and which also is automatically self-closing.

The invention comprises the construction 20 and arrangement of parts hereinafter described and claimed.

In the drawings, which represent one embodiment of the invention, Figure 1 is a sectional elevation on the line 1—1, Fig. 4, 25 through the upper portion of the receptacle, and showing the same closed; Fig. 2 is a similar view, showing the receptacle in position for pouring the liquid therefrom and with the cover open; Fig. 3 is a similar 30 view, showing the receptacle in position for filling from a tank; Fig. 4 is a plan view with the cover closed; and Fig. 5 is a sectional elevation on the line 5—5, Fig. 3, showing the cover open with the apron exposed.

The can or receptacle shown in the drawings is designed particularly for holding and carrying gasoline, illuminating oils or other combustible, volatile liquids, such as 40 from a tank wagon into a store or to any other delivery point. For safety in handling such liquids and to prevent the escape of volatile fumes or gases from the can in use thereof, and possible accidental ignition 45 of such fumes or gases or the contents of the can, it is preferably so arranged as to normally close automatically and tightly seal the discharge opening. At the same time the cover may be readily manipulated 50 to open the can either for filling the same at the tank or for pouring out the liquid at the delivery point, without the necessity of setting the can down or lifting off the cover and laying it to one side. Consequently the 55 receptacle is safe regardless of neglect or lack of attention by the driver.

In the form shown in the drawings the receptacle has a body portion 1 which may be of any suitable shape and is shown as of the usual cylindrical form with a reduced 60 neck 3 communicating with an inverted conical pouring or delivery spout 4 whose upper edge is preferably cut off on an incline. The can is also provided with the usual lifting and carrying bail 5, which is a 65 sheet metal bar or strap hinged or pivoted at 6 to the body of the can.

The opening at the mouth of the delivery spout is closed by a cover, one portion of which, marked 7, is rigidly or immovably 70 connected to the receptacle, as by being riveted or soldered thereto. This portion covers the rear part of the opening and forms a support for the movable part of the cover indicated at 8, the two cover members being connected by a suitable spring hinge 9 whose tension always tends to move the cover member 8 to the closed position shown in Fig. 1. The detailed construction of this spring hinge is immaterial and it 75 need not be further described. Said hinge, however, is preferably so located that its axis lies behind the forward straight edge of the stationary cover member 7, and the edge of the cover member 8 also extends beneath the axis of said hinge, so that in closed position of the cover, as shown in Fig. 1, the edges of the two members 7 and 8 overlap each other as shown at 10, consequently forming a very tight connection or 80 seal at this point and preventing the escape of volatile gases or fumes through the hinge joint when the cover is closed. To further seal the discharge opening the edges of the movable cover member 8 are provided with 85 a depending rim or flange 11 which extends below the edge of the inverted conical spout when the cover is closed. The cover is also reinforced in any suitable manner, such as by the longitudinal and transverse members 90 12 and 13, which are shown as metal straps riveted or otherwise secured to the outer face of the movable cover member and prevent accidental bending thereof or injury thereto.

Suitable means is provided for opening the cover, such as the finger hold 14, shown as a hook-like member riveted to the longitudinal reinforcing member 12 and lying near the outer edge of the cover 8. This 100 cover turns on a hinge axis which is above and parallel to the axis of turning move-

ment of the bail 5. Consequently, in filling the can with liquid it may be suspended from a spout or faucet 15 on the tank wagon, as shown in Fig. 2, with the cover 8 lying 5 behind the bail, in which position the weight of the can and its contents prevent the cover from closing. The receptacle can therefore be filled without any further attention on the part of the operator than merely placing 10 it in position on the spout or faucet. When the receptacle is filled the bail is moved forward to allow the cover to close and the liquid may then be carried safely to any suitable point for delivery.

15 Preferably, the receptacle is so arranged as to prevent the liquid from splashing out or escaping through the hinge joint between the two movable parts of the cover. This is accomplished in the receptacle shown by an 20 apron 16, which is a sheet metal member riveted or soldered to the inner surface of the movable cover member, and which, in open position of the cover, depends below and lies in front of the open hinge joint.

25 When the cover is closed the depending portion of said apron folds up underneath the stationary part 7 of the cover, as shown in Fig. 1.

In pouring the liquid from the receptacle 30 it is lifted by the bail, say with the right hand, the little finger of which is looped through the hook-shaped finger hold 14. By lifting the lower rear edge of the receptacle with the left hand it is tilted for pouring liquid and simultaneously the cover is 35 opened, as in Fig. 3. In this way any amount of liquid may be poured out of the receptacle as readily and as conveniently as with a receptacle whose top is entirely open.

40 When the proper quantity of liquid is

poured out the receptacle is tilted back to normal position and the cover automatically closes so that the liquid or any remaining gases or fumes cannot be ignited, due to inattention or neglect on the part of the driver. 45

This receptacle is very simple and can be manipulated readily for filling liquid thereinto or pouring it therefrom and protects the contents at all times from accidental ignition. Consequently, it increases materially the safety of handling volatile combustible liquids of this character. 50

What I claim is:—

1. A receptacle for use in carrying volatile, combustible liquids, comprising a body 55 portion having a neck and pouring spout, a bail pivoted upon said body portion, a cover hinged upon said pouring spout, a lifting member on said cover in position to be grasped by the same hand which supports 60 the receptacle at the bail, and spring means on said pouring spout tending to close said cover.

2. A receptacle for use in carrying volatile, combustible liquids, comprising a body 65 portion, a bail pivoted thereto, a cover hinged thereon, and an apron secured to the under surface of the hinged cover and in open position thereof depending below and lying in front of the hinge joint for covering the same and preventing escape of the liquid through said joint in filling the receptacle. 70

In testimony whereof, I have hereunto set my hand.

ROBERT B. COGAN.
